STARTER ON LOW-PRESSURE FLUORESCENT TUBULAR LAMPS

Fritz Knobel, Ennenda, Switzerland

Application February 21, 1947, Serial No. 729,960
In Switzerland March 2, 1946

2 Claims. (Cl. 315—100)

1

My present invention relates to improvements in starters for low-pressure tubular lamps with series reactors or chokes, comprising a break-contactor connected in series with the choke and biased by a hot wire so as to break upon passage of current and to cause, in combination with a condenser connected between the two electrodes, an automatic arcing of the fluorescent tube. The objects of my improvements are first to dispense with the resistor used in prior art for actuating the starting contactor, which resistor reduces the starting potential and thus impairs the starting operation, second to reduce the mass of the heating wire so as to render the starter readily responsive with a view of speeding up the starting operation, and third to substantially simplify the tube construction and the operative wiring by eliminating the heating of the electrodes and by using only a two-wire tube connection.

I attain these and related objects by the starter and the wiring schemes, shown by way of example, in the accompanying drawing, in which—

Fig. 1 is an elevation of the starter, with cover removed.

Fig. 2 a top plan view of Fig. 1,

Fig. 3 a wiring scheme of a starter on a fluorescent tube with heated electrodes, and

Fig. 4 a wiring scheme of a starter on a fluorescent tube with cold electrodes,

Fig. 5 a modified wiring scheme of a starter on a fluorescent tube with heated electrodes,

Fig. 6 an elevation of a starter modified relative to that shown in Fig. 1, and

Figs. 7 and 8 are cross-sections on lines VII—VII and VIII—VIII respectively of Fig. 6.

The starter according to Figs. 1 and 2 comprises a housing 1 of insulating material, in which all the parts are mounted. The two parts 2, 3 of the break-contactor shown are riveted, together with the appurtenant connecting lugs 4, 5 into housing 1, so that part 2 is electrically connected with lug 4, and part 3 with lug 5. Further, two studs 6, 7 are riveted to junction lugs 8, 9 to form an electrical connection. A bush 10 is pivoted on stud 7, and connected to an actuating arm 11. One end of a heating wire 12 is wound on bush 10, and the other end secured to stud 6. Heating wire 12 is kept stretched by a tension spring 13 engaging arm 11, and an insulating cap 14 carried on actuating arm 11 is situated in its position of rest at a certain distance from the movable contact portion 3 of the break contactor.

In the wiring diagram according to Fig. 3, one of the two terminals 15, 16, namely terminal 15,

is connected with junction lug 8 of heating wire 12, while a circuit is completed from the other junction lug 9 of heating wire 12 over thermo-fuse 17, reactor coil 18, terminal 19, heating electrode 20 of the fluorescent tube 21, terminal 22, junction lug 5, break-contactor 3, 2, junction lug 4, terminal 23, the other heating electrode 24 of tube 21, terminal 25, and the second reactor coil 26 to the other terminal 16, a starting condenser 27 being interposed between the terminals 19 and 25, which at the same time serves for radio dehumming.

When engaging the starter, the electrodes 20, 24, are heated at once, and heating wire 12 is expanded, thus turning actuating arm 11 in direction of the arrow shown in Fig. 1. Actuating arm 11, after covering a certain non-operative path, breaks contactor 2, 3 by virtue of insulating cap 14 biasing contactor portion 3, thus breaking the circuit, and heating wire 12 rapidly cools off again. The break-contactor is again closed, and such alternation is continued, until the fluorescent tube has been started. Current, now, flows continuously from network terminal 15 over lug 8, heating wire 12, lug 9, thermo-fuse 17, coil 18, terminal 19, electrode 20, through tube 21, electrode 24, terminal 25 and coil 26 to network terminal 16. Thus a current flows continuously through the heating wire 12, and break contactor 2, 3 is held broken.

The starter described, in contra-distinction to starters of prior art comprising glow relays or bi-metal contactors, possesses the advantage that no resistor connected parallel to the fluorescent tube is provided for actuating the starting contactor, which resistor reduces the starting potential and thus impairs starting. Further, the mass of the heating wire used is so small that the starter responds very quickly, and starting therefore, takes place rapidly.

In the wiring diagram according to Fig. 4, a fluorescent tube 28 with cold electrodes 29, 30 is used, which is connected to the terminals 31, 32. Further, a choke or reactor coil 33 is provided for. When switching on this starter, a circuit is completed from network terminal 15 over hot wire 12, thermo-fuse 17, choke coil 33, and break-contactor 3, 2 to network terminal 16. Contact 3, 2 thus is alternatingly made and broken, as in the first example, until an arc strikes along tube 28 by the action of the starting condenser 27 upon which a continuous flow of current takes place from network terminal 15 over hot wire 12, thermo-fuse 17, choke coil 33, terminal 32, electrode 30, tube 28, electrode 29, and terminal 31 to

network terminal 16, and break-contactor 2, 3 is held broken.

The example according to Fig. 4, as will be appreciated, substantially simplifies the tube construction and the wiring scheme, in that heating the electrodes may be dispensed with and only a two-wire connection is required for the tube.

The example according to Fig. 5 differs from that shown in Fig. 3 in that only one reactor 34 is provided for, and that heating wire 12 is connected, instead of in series with tube 21 and reactor 34, directly to a couple of turns of reactor 34. Heating wire 12 thus may be made sufficiently sturdy and heat-responsive also in case of a relatively small tube current. Further—and this is a point of particular interest—one and the same starter may be used for all types of tubes or instruments having different current ratings, an adaption only being necessary insofar as the number of turns between the end of reactor 34 and the tapping for the heating wire is chosen such that the voltage arising on the heating wire at rated current correspond to the requirements for each type of instrument.

The starter according to Figs. 6-8 differs from that shown in Fig. 1 in that the two studs 6, 7 supporting heating wire 12 are mounted by means of a metal transverse rail 35. Stud 6 is riveted to a rail 35 only, whereas lug 8 is secured to housing 1 by a rivet 36. An extension 37 of heating wire 12 is passed through housing 1 and soldered to lug 8. Stud 7, however, at the same time serves for connecting rail 35 to housing 1, passing through the latter and being riveted to lug 9. An insulating ring 38 is disposed between stud 7 and rail 35. By such arrangement of a metal transverse rail, heating wire 12 becomes independent of an expansion of housing 1, which expansion may be considerable for a Bakelite housing for example.

What I claim and desire to secure by Letters Patent is:

1. A low-pressure fluorescent tube starter comprising an insulating housing, a break-contactor mounted in the latter, two studs, a metallic rail secured in the said housing by one of the said

studs for independent expansion, a pair of lugs for electrical connection mounted outside the said housing and secured to said studs respectively, a washer insulating one of the said studs from said rail, a bush rotatable on one of the said studs, a heat-responsive wire disposed between the said studs and having one end secured to said bush, a spring-loaded arm secured to said bush, and an insulating cap mounted on the free end of said arm; the whole in such combination that the said contactor is broken through the swinging action of the said arm after the said wire has been heated, so that the current will pass through the fluorescent tube.

2. A starting device for a low-pressure fluorescent tube including a pair of tube electrodes, comprising in combination an insulating housing, a break-contactor mounted in the latter and connected in series with said electrodes, two studs, a metallic rail secured in the said housing by one of the said studs for independent expansion, a pair of lugs for electrical connection mounted outside the said housing and secured to said studs respectively, a washer insulating one of the said studs from said rail, a bush rotatable on one of the said studs, a heat-responsive wire disposed between the said studs and having one end secured to said bush, a spring-loaded arm secured to said bush, an insulating cap mounted on the free end of said arm, a single choke in circuit for said electrodes and means for connecting one terminal of said heat responsive wire to different intermediate points on said choke for the purpose of adapting one and the same starter to tubes of different current ratings.
